UNITED STATES PATENT OFFICE.

LAURENCE WEST WYMAN, OF OAKLAND, CALIFORNIA, ASSIGNOR TO CALIFORNIA CORRUGATED CULVERT COMPANY, OF OAKLAND, CALIFORNIA, A CORPORATION OF CALIFORNIA.

SHEET-METAL TANK.

1,319,826.

Specification of Letters Patent.

Patented Oct. 28, 1919.

Application filed September 12, 1918. Serial No. 253,714.

To all whom it may concern:

Be it known that I, LAURENCE WEST WYMAN, a citizen of the United States, residing at Oakland, in the county of Alameda and State of California, have invented certain new and useful Improvements in Sheet-Metal Tanks, of which the following is a specification.

My invention relates to the class of sheet-metal tanks, troughs, flumes, pipes and other sheet-metal structures which require an end-closure member.

My invention consists in the novel end connection which I shall hereinafter fully describe.

Though my invention is applicable to any sheet-metal structure of the class mentioned, it is especially adapted for stock-tanks or troughs, either for water or food, and in this connection it is found particularly useful for hog-troughs, in that it is sanitary, durable, and economical in manufacture.

Referring to the accompanying drawings:

Figure 1 is a cross section of my improved trough.

Fig. 2 is a longitudinal section, broken, on the line 2-2 of Fig. 1.

Fig. 3 is a top plan view, broken. Figs. 4 and 5 are detail views showing a slight modification of the top-lugs of the end members.

1 is the sheet-metal body of the trough, 35 bent in transverse section to any desired shape.

The end edges of the body 1 are beaded at 2, the bead being of any suitable shape. It may be circular or it may be arcuate, the 40 latter being here shown.

3 are the end-closure-members of the trough. These are of metal, in practice cast-metal, and each has on its inner face, near its border, a flange 4, the outer face of which 45 is formed into a seat 5 complementing the bead 2 of the end edges of the body 1.

The end-members 3 are formed below with feet 6, and at their tops they have inwardly projecting perforated lugs 7.

50 The end-members 3 are fitted to and overlap the end edges of the body 1, and their flanges 4 enter the body, the seats 5 of said flanges fitting and embracing the beads 2 of the body, as seen clearly in Fig. 2.

If desired, a suitable packing, such as a 55 coating of heavy paint, or paste, or mineral rubber, may be placed in the joint between the seat 5 and the bead 2, but to avoid confusion in the drawing, I have not deemed it necessary to show this.

When the end-members 3 are in place, the clamping-members which are here shown as rods 8 are fitted to the beads 2 by laying them in the concave exterior surfaces of said beads, the ends of the rods passing 65 through the perforated lugs 7 of the end-members; and said end receive the nuts 9.

It will now be seen that by tightening up the nuts 9, the rods 8 will clamp the beads 2 against the seats 5 of the flanges 4 of the 70 end-members 3, and thus make a secure and tight joint between the cast-iron end and the body of the trough.

10 are reinforcing rods in the side edges of the trough body. These may or may not 75 be used.

The shapes of the interfitting parts and the materials used may be varied without departing from the invention.

By the connection which I have herein 80 described, the cast-iron ends are satisfactorily fastened to the sheet-metal body without the use of rivets or solder, and they may be removed conveniently if required to more perfectly clean the trough.

As shown in Figs. 4 and 5, the perforated top-lugs 7 of the end members may assume the shape of separate cross plates 11.

I claim:

1. Sheet-metal tanks comprising a body-member, the end edge of which is beaded; an end-closure-member having a portion complementing and interengagingly fitting the bead of the body-member; and a clamping-member for tightening the complementary parts of the body-member and the end-closure-member together.

2. Sheet-metal tanks comprising a body-member the end edge of which is beaded; an end-closure-member having a flange on 100 its inner side with a face complementing and interengagingly fitting the bead of the body-member; and a clamping-member for tightening the bead of the body-member against the face of the end-member flange.

3. Sheet-metal tanks comprising a body-member the end edge of which is provided with a bead; an end-closure-member having

on its inner side a flange adapted to enter the end of the body-member, the face of said flange corresponding to and interengagingly fitting the exterior of the bead of said body-member; and a clamping-member fitted to the bead for tightening it in the flange.

4. Sheet-metal tanks comprising a body-member the end edge of which is provided with a bead; an end-closure-member having 10 a portion complementing and interengagingly fitting the bead of the body-member, and having also perforated members at its top; a clamping-member for tightening the

complementary parts of the body-member and the end-closure-member together, said 15 clamping-member passing through the perforated top members of the end-closure-member; and nuts on the ends of the clamping-member.

In testimony whereof I have signed my 20 name to this specification in the presence of two subscribing witnesses.

LAURENCE WEST WYMAN.
